FIG. 2

The surface decorations illustrated are repeated on the opposite side of the jar.

The dominant features of my design reside in the portions shown in full lines.

I claim:

The ornamental design for a jar, substantially as shown and described.
